CONNECTER END CAP

Albert C. Lusher, Waterbury, Conn., assignor to
Scovill Manufacturing Company, Waterbury,
Conn., a corporation of Connecticut

Application March 26, 1937, Serial No. 133,285

2 Claims. (Cl. 24—126)

The present invention relates to connectors for wires, cables and the like, and more particularly to an end cap or ferrule for application to the reduced open wire receiving end of the casing of the connector.

While the end cap of this invention is applicable to connectors of various constructions it is disclosed, for the purpose of illustration, as applied to the connector set forth in the copending application of William H. Barlow filed March 10, 1937 Serial No. 133,048.

An object of this invention is to provide a cap or ferrule which may serve as a guide and protector for overlapping the outer ends of the jaws 15 of the connector so that when inserting a stranded cable it is impossible for the strands to get in back of and caught on the jaws and so cause them to jam.

Another object is to provide a cap or ferrule 20 with a spring split or tongue portion extending into the open end of the connector to resiliently grip the cable or wire at a point outwardly of the ends of the jaws when retracted and in clamping position on the cable or wire; tending to act as a vibration dampener and prevent breakage of the cable at the mouth of the jaws.

A further object of the invention is to provide a cap or ferrule which serves as a gauge and reduces the diameter of the open end of the connector to a point where it is impossible to insert a cable or wire larger than that for which the particular connector is designed, and thus jam the connector.

A still further object is to provide a cap or ferrule which serves as a reinforcement for the end of the connector; which may be easily and inexpensively constructed and applied in position; which maintains the jaws open to the requisite extent to receive the cable; which prevents "necking" of the wire by the jaws produced by forming a substantially annular groove or depression in the wire to weaken the latter; and which may be attached to the connector by staking at a desired number of points.

With the foregoing and other objects in view, the invention will be more fully described hereinafter, and will be more particularly pointed out in the claims appended hereto.

In the drawing, wherein like symbols refer to like or corresponding parts throughout the several views:

Figure 1 is a side elevation, partly in section, of a connector having end caps embodying the features of this invention applied thereto, show-

ing the connector jaws in projected position with their outer ends underlapping the cap.

Figure 2 is a longitudinal section of the same taken axially at right angles on the line 2—2 of Figure 1, showing the jaws retracted from the cap, at the left end for receiving a wire and at the right end clamped on the wire.

Figure 3 is an enlarged fragmentary sectional view of the left end of the connector of Figure 1, showing the cap staked to the casing and the 10 spring guide tongues overlapping the jaws' ends for directing a wire or cable between the jaws.

Figure 4 is a detail perspective view of the cap.

Figure 5 is a detail enlarged perspective view of one of the connector jaws, showing the inner 15 side thereof with the beveled outer end, and

Figure 6 is a detail enlarged perspective view of the combined jaw retainer and spring cap of the connector.

Referring now to the drawing, the cap or ferrule of this invention is shown as applied to a connector of the construction disclosed in the above referred to copending application of William H. Barlow, wherein 10 designates a tubular casing having tapering open ends 11 through 25 which the wires or cables 18 may be introduced.

An expanding spring 13 is mounted in the casing 10 and has on each end a cap 14 with a jaw retainer projection 15 at its outer side about which are grouped a plurality of tapering jaws 16 30 slidably disposed in the adjacent tapering end 11 of the casing. As shown in Figures 1 and 3 the outer ends of the jaws 16 terminate, when freed of the wire 18, a short distance inwardly of the extremity of the tapering end 11 of the casing 35 and are normally urged into this projected position by the spring 13. The jaws 16 have beveled inner faces 17 at their forward ends acting as cam surfaces for the wire 18 to act against for retracting the jaws 16 and expanding the same, 40 as shown in Figure 2 at the left end, for admitting the wire 18 between the jaws and into the throat of the connector. The jaws 16 are provided with corrugated or otherwise roughened inner gripping surfaces 19 to engage the wire 18 45 when the jaws are urged outwardly by the spring 13.

The inner ends of the jaws 16 have studs 20 which extend inwardly and engage in radial openings 21 in the retainer projection 15 of the spring 50 cap.

The end cap or ferrule of this invention comprises a cap body 23 which is adapted to be fitted against the tapering open end 11 of the connector casing, and has an outer wall 24 which flares 55

to correspond to the taper of the casing end 11. The casing end 11 may have an annular exterior groove 25 over which the wall 24, or skirt of the cap, extends, and the cap 23 may be staked to the casing end 11 by a desired number, four being shown in the present instance, of punch points or projections 26.

The central portion of the cap 23 is turned inwardly or backwardly in the form of a combined gauge and guiding tube 27, which may be tapered slightly if desired as shown in Figure 3, and which has a desired number of slots 28 extending lengthwise from its inner end to a desired depth to provide a spring section 29 which may be, as shown, in the form of a plurality of spring tongues. This spring section 29 of the cap tube overlaps and bears more or less against the beveled faces 17 of the free ends of the jaws, when projected and free of the wire 18, so that the ends of the jaws 16 are held apart and are covered by the spring section 29 and so that the end of a wire or cable cannot strike the tips of the jaws 16 and cannot jam thereagainst as the wire or cable is introduced into the connector. This is particularly advantageous where a cable is used with the connector, as the strands of the cable have a tendency to separate or unravel and easily become caught against the tips of the jaws. This cannot occur with the use of the present cap.

This spring section 29 has an additional function as it yieldingly embraces the wire 18, as shown at the right end of Figure 2, when the wire is gripped between the jaws 16 and yieldingly supports the wire 18 at a point outwardly of and spaced from the adjacent ends of the gripping surfaces 19 of the jaws; dampening vibrations set up in the wire 18 and offsetting crystallization and breakage of the wire at the outer ends of the jaws 16.

The cap 23 may be of desired material, preferably of a spring metal material, and may be of desired thickness to perform the above described formation and to protect the tapering end 11 of the casing against damage in handling and in coupling wires and cables thereto. The outer wall or skirt 24 of the cap may have any suitable form to fit over the tapering end 11 of the casing and may be staked thereto by the punch points as above described, or may be secured to the casing end 11 in any other suitable manner.

To retract the jaws 16, particularly when releasing the wire 18 from the connector, the casing 10 has longitudinal slots 22 which opens the spring and caps 14 for the reception of an implement for engaging the caps to retract the same.

What is claimed is:

1. An end cap for a connector of the type having a tapering open ended casing and spring pressed jaws in the tapering end of the casing, comprising a cap body having a central inturned tapering tubular portion of substantially the diameter of a wire for insertion in the connector, said tubular portion having slots in its inner end providing yielding tongues for engagement with the wire to tension the same against vibration, said cap adapted to be secured over the open end of the casing with the inner end of the tubular portion spaced from the inner wall of the casing to receive thereabout and overlap the forward ends of the jaws when in initial forwardly pressed wire receiving position to guide the end of the wire centrally against and between the jaws.

2. An end cap for a wire connector having a casing with a tapering open end to receive a wire endwise therein and spring pressed jaws slidably mounted in said tapering end of the casing to engage the wire when inserted comprising an end cap adapted to be secured over the open extremity of said tapering end of the casing and having an inturned tubular central portion to project into said open extremity of the tapering end of the casing and having an internal diameter of substantially the gauge of a wire to be inserted to determine the correct size of a wire for the opening between the jaws, said tubular central portion of the cap having its inner end reduced and slotted to provide a plurality of converging spring tongues for yielding engagement with the wire when inserted to tension the wire against vibration, the inner end of the tubular central portion of the cap adapted to provide an annular space thereabout within the tapering end of the casing for the reception of the outer ends of the jaws when spring pressed into initial wire receiving positions, whereby the said tubular central portion of the cap may guide the end of a wire centrally into position against and between the jaws.

ALBERT C. LUSHER.
